UNITED STATES PATENT OFFICE.

DANIEL G. BOLTON, OF CAMDEN, NEW JERSEY.

SASH-LOCK.

SPECIFICATION forming part of Letters Patent No. 783,013, dated February 21, 1905.

Application filed January 5, 1904. Serial No. 187,797.

To all whom it may concern:

Be it known that I, DANIEL G. BOLTON, a citizen of the United States, residing at Camden, in the county of Camden and State of New Jersey, have invented a certain new and useful Improvement in Sash-Locks, of which the following is a specification.

The invention while capable of use in other connections and for other purposes is particularly designed for utilization as a window-lock, the object being to provide a device of this character which shall be simple and durable in construction and reliable in operation.

A further object is to provide a lock which shall securely maintain the parts engaged in their proper relation, resisting all ordinary effort of an unauthorized individual to tamper with the mechanism and release such engaged parts.

In carrying out the invention in an approved form, as embodied in a window-lock, I secure the same to the top of the lower sash of a window, providing the lower portion of the upper sash, as well as the adjacent jamb in which both sashes operate, with suitable recesses, with which or with certain of which coact bolts forming part of the lock and one or more being preferably spring-pressed to engaging positions. Said bolts are interdependent, and co-acting with one or both thereof is a series of retracting-plungers arranged in such relation to said bolts or one of them as that their operation will withdraw said bolt or bolts from engaging position in order to release the sash and permit the window to be opened. The construction is such that one or both sashes may be locked at any desired position in the jamb, thereby making it possible to leave the window open, as for the purpose of ventilation, while at the same time guarding against unauthorized intrusion.

The invention is illustrated in the accompanying drawings, in which—

Figure 1 is a side elevation illustrating the invention, one of the sections of the inclosing casing being removed. Fig. 2 is a horizontal section on the line 2 2, Fig. 1. Fig. 3 is a cross-section on the line 3 3, Fig. 1; and Fig. 4 is a bottom view.

Referring to the drawings, in which similar

letters denote corresponding parts, A designates the window-jamb, B the lower sash, and C the upper sash. Said jamb A and sash C are provided with a series of recesses a c , and, if desired, each of these may be provided with a bushing a' c' , secured in position by means of screws a^2 c^2 . As clearly shown in Fig. 1, the lock mechanism is mounted on the top of the lower sash B within a two-part casing D, the members whereof may be secured together by screws d . The under side of said casing is provided with keyhole-slots D' in order that after the screws D^2 have been placed in position the enlarged portions of said slots may be placed over the heads and the casing forced forward, so as to lock the bottom member thereof firmly under the heads of said screws. Any other preferred method of attachment may be used—as, for instance, integral ears formed on the casing and perforated for the reception of screws.

E designates the main bolt, here shown as provided at its forward end with the tubular member e , operating through orifice e' in the casing and having inside of said casing the shoulder e^2 . The other end of said bolt is provided with two rearwardly-projecting extensions e^3 e^4 , operating in orifices e^5 e^6 in the rearward portion of said casing D. Said extension e^3 is preferably provided with a coil-spring e^7 , exerting a tendency to press the bolt E forwardly to engaging position. The primary function of extension e^4 is to prevent the bolt E from turning. The under side of said bolt E is provided with ears e^8 e^9 , the function whereof will be presently described. The under side of said bolt E is also provided with two cut-away or recessed portions e^{10} e^{11} in such proximity as to form between them a tooth e^{12} . As shown in Figs. 1 and 2, the forward end of said bolt E is adapted to coact with the recesses in the jamb A.

F designates a bolt arranged at right angles to the bolt E, the inner end operating through an orifice f' in the lock-casing and coacting with one of the recesses c formed in the upper window-sash C. The front end of said bolt F is of less diameter and operates through orifice f^2 in the forward member of said casing D. Said bolt is provided with an integral

ear f^3 , carrying a pin f^4 , operating through an orifice in the rear member of the casing and provided between said casing and said ear with a coil-spring f^5 , the tendency whereof is 5 to withdraw said bolt from engaging position, in which it is shown in Figs. 1, 2, and 3. The primary function of said pin f^4 is to prevent said bolt from turning. The bolt F is provided with a recess f^6 and next to this a deeper 10 recess f^7 . The bolt F directly underlies the recess e^{11} of the main bolt E when both bolts are in engaging position, the purpose whereof will be presently explained.

G G' designate bolt-operating plungers, 15 each having a beveled forward end g adapted to coact with the similarly-beveled forward faces of the ears e^8 e^9 on the under side of the main bolt E. Each of said plungers operating through orifices in the casing D, as clearly 20 shown in Fig. 2, is provided inside of said casing with arms g' , carrying pins g^2 g^3 , operating through orifices in the rearward member of the casing, said pins g^2 carrying coil-springs g^4 , the tendency whereof is to force said plungers G G' outwardly to non-engaging 25 position.

The purpose of the bolt-operating plungers G G' is to withdraw the main bolt E from engaging position by the coaction of the beveled 30 surfaces g of said plungers with the correspondingly-beveled surfaces of the ears e^8 e^9 . This, however, may not be done until the bolt F has been pressed even farther than normally 35 into its coacting recess c , as will now be explained.

The locking or engaging position of the mechanism is illustrated in Figs. 1, 2, and 3. In this position the forward ends of the bolts E and F are located within one of the recesses 40 a and one of the recesses c . To unlock the mechanism—that is, to throw the bolts to non-engaging or inoperative position—it is necessary first to press inwardly the bolt F even farther than it normally extends to coact with the recess c , for in its normal position rearward movement of the bolt E is precluded by the tooth e^{12} , which coacts with the recess f^6 . After bolt F has been pressed inwardly, however, the deeper recess f^7 is brought into the 45 path of said tooth e^{12} , and bolt F therefore offers no obstruction to the rearward movement of said bolt E against the tension of its actuating-spring e^7 . Therefore upon pressing inwardly the bolt-operating plunger G the bolt E is so pressed rearwardly through the coaction of the cam-surface g of said plunger and that of the ear e^8 , thereby bringing the recess e^{10} in line with the main body of the bolt F and removing any obstacle to the passage 50 of said bolt F. Under the influence of the spring f^5 , therefore, said bolt F will quickly move to non-engaging position as soon as the recess e^{10} comes into alinement with it. By this means both the main bolt E and the 55 bolt F may be withdrawn from engaging position.

sition and the sashes moved relatively to each other.

If the rearward movement of the main bolt E under the influence of the plunger G be insufficient to free said bolt from its recess, the 70 plunger G' may be operated to move it still farther rearwardly through the coaction of its cam end with the cam-face of the ear e^9 . In fact, there may be any number of these plungers, and, if desired, some of them may be 75 blind or inoperative, so that pressure only upon certain plungers will result in the rearward movement of the bolt E essential to throw both said bolt E and the bolt F to inoperative or non-engaging position. A lock 80 so constructed offers an efficient safeguard against unauthorized operation.

To relock, it is necessary only to push inwardly the cross-bolt F. This will bring the deep recess f^7 into alinement with the tooth e^{12} of the main bolt E, whereupon said bolt E will snap to engaging position under the influence of the spring e^7 .

What I claim, and desire to secure by Letters Patent, is—

1. In a lock, the combination with a casing, a bolt spring-pressed toward engaging position and another bolt arranged at an angle thereto, both said bolts coacting with sockets or recesses outside said casing, of a retracting- 95 plunger arranged at an angle to the bolt first named and in a plane parallel with said angularly-arranged bolt and adapted to be manually operated, substantially as set forth.

2. In a lock, the combination with a bolt 100 spring-pressed toward engaging position, of a series of retracting-plungers arranged at an angle thereto and adapted to be manually operated to coact successively with said bolt, substantially as set forth.

3. In a lock, the combination with a casing, a bolt spring-pressed toward engaging position and another bolt arranged at an angle thereto, both said bolts coacting with sockets or recesses outside said casing, of a retracting- 110 plunger arranged at an angle to the bolt first named and in a plane parallel with said angularly-arranged bolt and adapted to be manually operated, said plunger having a cam or wedge shaped portion engaging with the bolt 115 first named, substantially as set forth.

4. In a lock, the combination with a main bolt, of a bolt arranged at an angle thereto and adapted, in one (inoperative) position, to secure said main bolt against forward or engaging movement, and a retracting-plunger having a cam or wedge shaped portion coacting with said main bolt, substantially as set forth.

5. In a lock, the combination with a main 125 bolt spring-pressed toward engaging position, of a bolt arranged at an angle thereto and adapted, in one (inoperative) position, to secure said main bolt against forward or engaging movement, and a retracting-plunger having 130

- a cam or wedge shaped portion coacting with said main bolt, substantially as set forth.
6. In a lock, the combination with a main bolt having a projection, of an independently-operable bolt arranged at an angle to said main bolt and having a recess, said bolt, in one position, coacting with said projection to preclude forward movement of said main bolt, and, in another, permitting said projection to pass through said recess, substantially as set forth.
7. In a lock, the combination with a bolt spring-pressed toward engaging position, of an independently-operable stop arranged in juxtaposition thereto and adapted in one position to preclude rearward movement of said bolt and in another to permit said bolt to be retracted, a cross-bolt combined with said stop operable to engaging position, and directly-coacting cam-plungers for moving said bolt to retracted position, substantially as set forth.
8. In a lock, the combination with a bolt spring-pressed toward engaging position and having two recesses and a tooth between the same, of a cross-bolt spring-pressed toward retracted position and having a recess, each of said bolts in one or another of its several positions acting as a stop to the other, substantially as set forth.
9. In a lock, the combination with a main bolt spring-pressed toward engaging position and having two recesses and a tooth between the same, of a cross-bolt spring-pressed toward retracted position and having a recess adapted to coact with said tooth, said cross-bolt coacting with one of said recesses in one position of the main bolt to permit movement to retracted position and with the other, in another position of said main bolt, to move to retracted position, substantially as set forth.
10. The combination with a bolt spring-pressed toward engaging position and having means for preventing said bolt from turning, of rigid ears formed on said bolt and a plunger spring-pressed to retracted position but adapted under pressure to make sliding contact with said ears to move said bolt to non-engaging position, substantially as set forth.
11. The combination with a bolt spring-pressed toward engaging position and having means for preventing said bolt from turning, of rigid ears formed on said bolt and a series of plungers spring-pressed to retracted position but adapted under pressure to make sliding contact with said ears to move said bolt to non-engaging position, substantially as set forth.
12. The combination with a casing, a main bolt, a cross-bolt and a plunger for retracting said main bolt, of projections or extensions connected with each of said bolts and with said plunger and coacting with orifices in said casing to prevent disarrangement thereof, substantially as set forth.
13. In a lock, the combination with a casing having orifices, of a main bolt therein operating through an orifice in said casing and having a shoulder limiting its forward movement, said bolt being spring-pressed toward engaging position and having a rearward extension operating through an orifice in said casing, a cross-bolt underlying said main bolt and having means for preventing its displacement, both ends of said cross-bolt projecting through orifices in said casing, said main bolt and cross-bolt being interdependent, and a series of plungers operating through orifices in said casing and having cam or wedge shaped ends coacting with ears carried by said main bolt to move the same to non-engaging positions, said plungers having means for preventing displacement and being spring-pressed toward retracted and inoperative position, substantially as set forth.

This specification signed and witnessed this 31st day of December, 1903.
